UNITED STATES PATENT OFFICE.

EDMOND ROSENBERG, OF PARIS, FRANCE, ASSIGNOR TO GENERAL ELECTRIC COMPANY, A CORPORATION OF NEW YORK.

CABLE-REEL.

No. 882,587.

Specification of Letters Patent. Patented March 24, 1908.

Application filed August 16, 1907. Serial No. 388,825.

To all whom it may concern:

Be it known that I, EDMOND ROSENBERG, a citizen of the French Republic, residing at Paris, France, have invented certain new and useful Improvements in Cable-Reels, of which the following is a specification.

My invention relates to cable reels and particularly to that form of reel used on mining locomotives. These reels serve to wind up and pay out a flexible conductor which may be attached at one end to a source of current, such as a trolley wire, and which supplies current to the locomotive when it is "gathering" cars from the working faces of the rooms of mines. By using a flexible cable and a reel in this way, the necessity of having trolley wires over short spur tracks is avoided.

An object of my invention is to provide a new and improved construction of reel and a simple means for driving the same and keeping the flexible conductor under a constant tension.

My invention will be more fully understood and the advantages thereof evident from the following description which, when taken in connection with the drawing, sets forth one form of apparatus in which my invention may be embodied.

Referring to the drawing, in which like parts are denoted throughout the several views by the same reference characters, Figure 1 is a more or less diagrammatic side elevation of a locomotive equipped with my invention; Fig. 2 is a plan view thereof; and Fig. 3 is a sectional elevation through the reel shown in Figs. 1 and 2.

The frame of a mining locomotive is shown at 5. This may be driven by motors geared to the axles and controlled through a suitable controller (not shown) in the usual manner. As is usual in locomotives of this kind, the cable reel is mounted on the top thereof and a flexible conductor 6 passes through a guide 7 and is attached at one end to a source of current supply, such as the trolley wire 8.

In the form of reel shown a supporting frame 10 is secured to the top of the locomotive. This frame carries a rotatable driving member 11 on the bottom of which is an annular rack 12 which is engaged by a pinion 13 on a shaft 14 mounted in a bearing in the frame 10, as shown in Fig. 3. The shaft 14 carries a sprocket wheel 15 which is driven by a chain 16 running over a sprocket secured to

one of the axles of the locomotive. A winding drum 17 which may be of any suitable construction, as for instance strips of sheet metal suitably bent and fastened together, is supported on a flange 18 which is a part of the driving member 11. A suitable washer 19 may be interposed between the flange 18 and the frame 20 of the drum 17. A positive but yielding driving connection is interposed between the driving member 11 and the winding drum 17. This consists of a spiral spring 21 secured at its inner end 22 to the hub of the driving member 11 and at its outer end 23 to the inside of the drum 17.

The flexible conductor 6, which serves to convey current to the motors of the locomotive, is brought through an opening in the drum 17 and is secured at its inner end to a binding post 25 insulated from the frame of the reel. This binding post is connected by a spring or finger 26 with a suitable contact plate 27. The under side of this contact plate 27 is held against the end of a contact member 28 which is secured to the conductor 29 carrying current to the motors. A number of other springs 26' may be attached to the contact plate and serve to hold it firmly against the contact member 28. The contact member 28 and the springs 26 and 26' are insulated from the frame of the reel as shown.

The operation of my improved reel is obvious. The spiral spring 21 is originally placed under tension and this tension is constantly exerted on the flexible conductor 6, thereby keeping said conductor more or less taut. As the locomotive moves back and forth the reel is rotated in one direction or the other by means of the driving connection between the reel and axle. The sprocket wheels and gearing are, of course, so proportioned that the reel winds and unwinds at the same rate as the locomotive moves. The reel therefore takes up and pays out the proper amount of conductor and the tension exerted by the spiral spring remains unchanged. The cable is thus properly taken care of.

While I have shown one particular form of my invention, I wish it understood that I realize that this construction may be varied to a considerable extent without departing from the spirit of my invention. It is my intention to cover all such modifications in the claims hereto appended.

What I claim as new and desire to secure by Letters Patent of the United States, is—

1. In combination, a vehicle arranged for forward and reverse movement, a cable reel carried thereby, a flexible cable having one end connected to said reel and the other secured at a fixed point, and a positive but yielding driving connection between said reel and a part which rotates with the movement of the vehicle.
2. In combination, a movable vehicle, a cable reel carried thereby, a flexible cable having one end connected to said reel and the other secured at a fixed point, and a spring driving connection between said reel and a part which rotates with the movement of the vehicle.
3. In combination, a movable vehicle, a cable reel carried thereby, a flexible cable having one end connected to said reel and the other secured at a fixed point, and a spring driving connection between said reel and axle of the vehicle.
4. In combination, a movable vehicle, a cable reel carried thereby, a flexible cable having one end connected to said reel and the other secured at a fixed point, a driving member, a spring serving as a yielding connection between said reel and said driving member, and means for causing a positive rotation of said driving member in both directions.
5. In combination, a movable vehicle, a

cable reel carried thereby, a flexible cable having one end connected to said reel and the other secured at a fixed point, a driving member, a spring serving as a yielding connection between said driving member and said reel, and a positive driving connection between said driving member and a part which rotates with the movement of the vehicle.

6. In combination, a movable vehicle, a cable reel carried thereby, a flexible cable having one end connected to said reel and the other secured at a fixed point, a driving member on said vehicle, a spring serving as a yielding connection between said driving member and said reel, and a positive driving connection between an axle of the vehicle and said driving member.

7. In combination, a movable vehicle, a cable reel carried thereby, a flexible cable having one end connected to said reel and the other secured at a fixed point, a driving member, a spring normally under tension and serving as a driving connection between said member and said reel, and a positive driving connection between said member and an axle of the vehicle.

In witness whereof, I have hereunto set my hand this fifth day of August, 1907.

EDMOND ROSENBERG.
